FIRE ALARM ACTUATOR

Walter H. Johnson, Tacoma, Wash.

Application January 18, 1954, Serial No. 404,521

12 Claims. (Cl. 116—101)

This invention relates to a fire alarm actuator and more particularly to a device which contains a supply of gas under pressure or a liquid which gas or liquid will be released when the pressure thereof exceeds a predetermined amount.

An object of this invention is to provide a fire alarm actuator comprising a container having a resilient portion which is distended and severed when the pressure of gas in the container is increased due to an increase of temperature surrounding the container.

Another object of this invention is to provide a fire alarm actuator wherein the effectiveness of the actuator is not reduced due to the age of the device.

A further object of this invention is to provide a fire alarm which will have a prolonged period of actuation.

A still further object of this invention is to provide a fire alarm actuator which is simple and efficient in construction and durable and lasting in use.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is an exploded perspective view of one form of fire alarm forming the subject of this invention;

Figure 2 is a side elevational view with parts shown in section of the form of fire alarm illustrated in Figure 1;

Figure 3 is a perspective view of the severing means used in connection with the fire alarm of Figure 1;

Figure 4 is an exploded perspective view of a modified fire alarm actuator forming the subject of this invention;

Figure 5 is a perspective view showing the modified fire alarm actuator of Figure 4 in assembled position;

Figure 6 is a sectional view taken substantially along section line 6—6 of Figure 5;

Figure 7 is a sectional view showing the fire alarm actuator of Figure 4 mounted for use with a bell type fire alarm;

Figure 8 is a top plan view showing the fire alarm actuator of Figure 4 mounted for use with a switch in an electrical fire alarm circuit;

Figure 9 is a sectional view taken substantially along the section line 9—9 of Figure 8.

Referring now more particularly to the accompanying drawings it will be seen that the improved fire alarm illustrated in Figure 1, includes a container 10 having an outlet 12 secured thereto. The container 10 may be of metal or any other suitable material and is filled with a gas which is non-inflammable and non-poisonous.

The outlet 12 is internally threaded as at 14. Disposed within the outlet 12 is an externally threaded portion 16 having a diaphragm of resilient material 18 secured thereto. The diaphragm 18 is adapted to seal the outlet 12. Secured in the outlet 12 above the diaphragm 18 is an externally threaded bushing 20. The bushing 20 extends beyond the end of the outlet 12. The bushing

2

20 is provided with a wire cage 22 extending upwardly therefrom. The wire cage 22 is shaped in a cone similar to the expected shape of the diaphragm 18 when the diaphragm is distended due to an increase in pressure of the gas within the container 10. The members of the wire cage 22 are provided with knife-like edges facing the diaphragm 18. The configuration of these members can be more clearly seen in Figure 6.

An adaptor 24 is provided with an internally threaded end 26 for engagement on the portion of bushing 20 which extends beyond the end of outlet 12. The other end of the adaptor 24 is externally threaded as at 28. A whistle comprising a cylindrical housing 30 closed at both ends and having an inlet 32 secured to the housing 30 mid-way of its length. The outer end of the inlet 32 is provided with an internally threaded portion 34 which engages the threaded portion 28 on adaptor 24. The housing 30 is provided with a notch 36 adjacent the connection of the inlet 32 to the housing 30. The notch 36 extends completely through the wall of the housing 30.

A transverse slot 38 is provided at each end of the housing 30 and extends through the wall of the housing. A reed 40 is mounted within the housing 30 overlying each of the slots 38.

In practical use of the device shown in Figure 1, the device is assembled and placed in a convenient position within a building. In the event that fire breaks out in the building the temperature surrounding the container 10 will be increased which will cause the gas within the container 10 to expand. The diaphragm 18 will be distended until it engages the wire cage 22 and further expansion of the gas within the container 10 will cause the wire cage 22 to sever the diaphragm 18. When the diaphragm 18 is severed the gas within the container will be allowed to pass through the adaptor 24 and inlet 32 into the housing 30. The initial gas being under extreme pressure will cause the reeds 40 to seal against the slots 38. The gas will be allowed to escape through notch 36 causing a whistling sound. As the pressure of the gas declines the whistle will become less effective but will be supplemented by the actuation of the reeds which will operate at the decreased pressure. Therefore, the combination of the notch 36 and the reeds 40 will provide means whereby the effectiveness of the signal will be prolonged.

Figures 4, 5 and 6 illustrate a form of actuator to be used in conjunction with various types of fire alarm systems. In this embodiment, a container 42 is formed of a resilient material and filled with a non-inflammable and non-poisonous gas or liquid. A collapsible wire cage is provided for severing the container 42 when the container is distended due to an increase of pressure within the container caused by an increase of the temperature surrounding the container.

The wire cage shown in Figures 4 to 6 is formed of a lower section 44 and an upper section 46 which will move together when the container 42 is collapsed. The section 44 is formed of a circular base member 48 having a plurality of longitudinally extending members 50 extending upwardly and outwardly therefrom. The upper ends of members 50 are connected together by a ring 52. The length of members 50 is such that when the base 48 engages one end of the cylinder 42 the ring 52 will be disposed substantially mid-way along the container 42.

The upper section 46 is formed of a top member 54 having a plurality of downwardly and outwardly extending longitudinal members 56 secured thereto. The lower end of the members 56 extend radially outwardly as at 58. When the lower section 44 and the upper section 46 are disposed about the container 42 the radially outwardly extending ends 58 of members 56 will engage the lower surface of the ring 52 for retaining the sections in

position on the container 42. When the container 42 is collapsed the upper section 46 will be free to move within the lower section 44.

The members 50 and 56 are provided with inwardly facing knife edges 60, as shown in Figure 6. As the container 42 is distended to the increase of pressure within the container the knife edges 60 will sever the container to allow the gas therein to escape whereby the container 42 will collapse.

The container 42 is provided with outwardly extending projections 62 at each end thereof. The base 48 is provided with a central aperture 64 for receiving one of the projections 62 and the top member 54 is provided with an aperture 66 for receiving the other projection 62. By the engagement of the projection 62 in the apertures 64 and 66 the container 42 will be centrally positioned within the wire cage.

Figures 7, 8 and 9 show the actuator of Figures 4, 5 and 6 used in connection with various fire alarm systems. In the system illustrated in Figure 7 there is provided a mounting plate 68. Bolts 70 extend from the mounting plate 68 and are adapted to receive on their other ends a plate similar to plate 68 and spaced parallel thereto. Secured to the plate 68 adjacent one end is a shaft 72. Parallel to shaft 72 and spaced therefrom is a shaft 74 mounted for rotation on the plate 68. A coil spring 76 is wound about the shaft 74 and fixedly secured at one end to the shaft 74 and secured at its other end to shaft 72. Also secured to the shaft 74 for rotation therewith is a large gear 78. A shaft 80 rotatably mounted on the plate 68 supports a gear 82 for meshing engagement with the gear 78. The gear 82 is fixedly secured to the shaft 80 for rotation therewith.

Secured to the shaft 80 is a crank arm 84 having a pin 86 extending from one side thereof. A clapper 88 is pivotally mounted intermediate its ends on a shaft 90 secured to the plate 68. One end of the clapper 88 is provided with a longitudinally extending slot 92 which receives the pin 86 on crank arm 84. Thus, when the spring 76 is tensioned and released gear 78 will drive gear 82 which in turn will drive shaft 80 and crank arm 84 to cause the pin 86 to oscillate clapper 88 about the pivot 90.

The other end of clapper 90 is provided with a mallet 94 which strikes a bell 96 mounted on a pin 98 secured to a covering 100 which extends between the mounting plate 68 and the plate spaced parallel thereto.

One side of the covering 100 is provided with a longitudinal slot 102 through which the clapper 88 extends. Extending between the mounting plate 68 and its parallel plate is a platform 104 positioned below the clapper 88 and between the pivot 90 and the slot 102. The actuator illustrated in Figures 4, 5 and 6 is adapted to be mounted in a vertical position on the platform 104 and engaging the clapper 88 to retain the same in its uppermost position.

In practical use of the device illustrated in Figure 7 when the spring 76 is tensioned and the actuator is placed on the platform in engagement with the clapper 88 the actuator will restrict the movement of the clapper. However, when the container 42 has been severed and the section 46 moves within the section 44 the clapper 88 will be released whereby the spring will drive gears 78 causing the mallet 94 to strike the bell 96. This operation will continue until the spring 76 has run down.

In the embodiment shown in Figures 8 and 9 there is disclosed an electrical circuit for a fire alarm system. A switch plate 106 is provided which has a horizontal portion 108 spaced vertically from and parallel to a horizontal portion 110. Pivotally mounted at one end of portion 108 are a pair of switch arms 112. The portion 108 is provided with a recess 114 into which an end of arms 112 extend and pins 116 extend through the recesses 114 and through the arms 112 for providing a pivot for the arms 112.

The arms 112 are interconnected by a plate 118. The

plate 118 is formed of insulated material and is positioned on the arms 112 at a point overlying portion 110. A leaf spring 120 is fastened at one end to portion 108 by fasteners 122 and has the other end thereof overlying the upper surface of plate 118. The leaf spring 120 will urge the arms 112 toward the portion 110. Electrical conductors 124 are connected to the end of portion 108. Screws 126 secure the conductors 124 to the portion 108. Spring clips 128 are connected to the screws 126 and overlie the ends of the arms 112 for providing an electrical connection between the conductors 124 and the arms 112.

Electrical conductors 130 are connected at one end to the end of portion 110 opposite the portion 108. Extending upwardly from the connection of conductors 130 to the plate 110 are contacts 132. The contacts 132 are positioned so as to be engaged by the ends of arms 112 when the arms 112 are urged downwardly by the spring 120.

20 The actuator of Figures 4, 5 and 6 is adapted to be positioned in vertical relation on the portion 110 and engaging the plate 118. When the container 42 is completely filled the actuator will maintain the arms 112 out of contact with the contacts 132. However, when the 25 gas has been released from container 42 the air cage will collapse allowing the spring 120 to urge the arms 112 into contact with the contacts 132. This will close the circuit between the conductors 124 and 130 and cause the fire alarm signal to be actuated.

30 The conductors 130 may be connected to a suitable source of electricity and conductors 124 may be connected to a suitable fire alarm signal. The switch plate 106 is formed of insulating material so that the electricity cannot pass therethrough from conductor 124 to conductor 130 unless the switch is closed.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

45 What is claimed as new is as follows:

1. A fire alarm actuator comprising a container adapted to be filled with a supply of gas under pressure, said container having a resilient portion adapted to be distended due to an increase of pressure of the gas within the container and means mounted adjacent said portion for severing said portion to release said gas when said portion is distended a predetermined amount.

2. The combination of claim 1 wherein said means 50 comprises a wire cage surrounding said resilient portion, said wire cage being provided with knife-like edges facing said resilient portion.

3. A fire alarm comprising a container adapted to be filled with a supply of gas under pressure, said container having an outlet therefrom, a flexible diaphragm 60 mounted in said outlet for closing the same, a conduit connecting said outlet to a signal device, means mounted in said conduit above said diaphragm to sever said diaphragm when the diaphragm is distended due to an increase of pressure of the gas within the container 65 whereby said gas will be released to activate said signal means.

4. The combination of claim 3 wherein said means 70 comprises a wire cage mounted in said conduit and overlying said diaphragm, said cage being provided with knife-like edges facing said diaphragm.

5. A fire alarm comprising a signal device, means for actuating said signal device, said means including a container having a supply of gas under pressure, said container having a resilient portion adapted to be distended 75 by an increase of pressure of the gas within the container

and means mounted adjacent said portion for severing said portion to release said gas when said portion is distended to a predetermined amount whereby said signal device will be operated.

6. The combination of claim 5 wherein said signal means comprises a whistle, a conduit connecting said whistle to said container, a diaphragm in said conduit sealing the same and means in said conduit for severing said diaphragm when said diaphragm is distended due to an increase in pressure of the gas in the container whereby said gas passes through the conduit to the whistle to actuate the same.

7. The combination of claim 5 wherein said signal device, includes a bell, a clapper for said bell, drive means for actuating said clapper, said container being formed of a body of resilient material, said releasing means comprising a collapsible wire cage surrounding said container, said cage being provided with knife-like edges facing said container whereby said container will be severed by said cage when the container is distended due to an increase in pressure of the gas in the container, said cage and container engaging said clapper to prevent movement of the clapper when the container is full, said wire cage collapsing when the gas is released from said container to allow said clapper to be actuated to strike the bell.

8. The combination of claim 5 wherein said signal device includes a plurality of electrical conductors, switch means disposed between said electrical conductors, spring means urging said switch means to a closed position, said container being formed of a body of resilient material, said releasing means comprising a collapsible wire cage surrounding said container, said cage being provided with knife-like edges facing said container whereby said container will be severed by said cage when the container is distended due to an increase in pressure of the gas in the container, said cage and said container engaging said switch means to maintain the switch in open position when the container is full, said cage collapsing when the gas is released from said container to allow said spring to urge said switch means to closed position.

9. The combination of claim 3 wherein said signal means includes a longitudinal cylinder closed at both ends, said conduit being connected to said cylinder midway

of its length, said cylinder having a notch therein adjacent the connection of said conduit thereto, said cylinder being provided with a transverse slot adjacent each end thereof and extending therethrough, and a reed mounted in said cylinder and overlying said slots.

10. A fire alarm actuator comprising a resilient container having a supply of gas under pressure therein, a wire cage surrounding said container, said cage being formed of upper and lower sections, said lower section being formed of a base member a plurality of upwardly and outwardly extending longitudinal members secured to said base member, a ring member connected to the upper ends of said longitudinal members, said upper section being provided with a top member, a plurality of downwardly and outwardly extending longitudinal members secured to said top member, the lower ends of said longitudinal members extending radially outwardly, said upper and lower sections adapted to be positioned over the container with the radially outwardly extending portions of the upper longitudinal members engaging the lower surface of said ring member.

11. The combination of claim 10 wherein said longitudinal members on the upper and lower sections are provided with knife-like edges facing the container whereby the container will be severed by the members when the container is distended due to an increase in pressure of the gas within the container.

12. The combination of claim 11 wherein said container is provided with a projection extending from each end thereof, said base member and said top member being each provided with a central aperture for the reception of said projections whereby said container will be centrally positioned within said cage.
